UNITED STATES PATENT OFFICE.

RICHARD G. THOMAS, OF CLEVELAND, OHIO, ASSIGNOR, BY MESNE ASSIGNMENTS, TO THE AUTOMATIC ADDRESSING MACHINE COMPANY, OF CLEVELAND, OHIO.

PRINTING AND ADDRESSING MACHINE.

1,208,860.

Specification of Letters Patent. Patented Dec. 19, 1916.

Application filed November 22, 1910. Serial No. 593,642.

To all whom it may concern:

Be it known that I, RICHARD G. THOMAS, a citizen of the United States, residing at Cleveland, in the county of Cuyahoga and 5 State of Ohio, have invented a certain new and useful Improvement in Printing and Addressing Machines, of which the following is a full, clear, and exact description.

This invention relates to printing machines, and particularly to printing and addressing machines of the type which prints the same subject matter on one side of each of a number of cards or other blanks and at the same time prints different addresses on 15 the opposite sides.

The object of the invention is to provide a printing and addressing machine which is more efficient and satisfactory in operation than those which have been constructed heretofore; which is simple in construction and contains no parts which are liable to get out of order and which prints and addresses blanks very effectively and with great 25 rapidity. These and other objects are attained by my invention which may be briefly summarized as consisting in certain novel details of construction and combinations and arrangements of parts which will be described in the specification and set forth in 30 the appended claims.

In the accompanying sheets of drawings, Figure 1 is a front elevation of the operating mechanism of a printing and addressing machine constructed in accordance with my 35 invention; Fig. 2 is a top plan view of the same; Fig. 3 is a transverse sectional view substantially along the line 3—3 of Fig. 2, looking in the direction indicated by the arrows; Fig. 4 is a partial longitudinal sectional view substantially along the line 4—4 of Fig. 2, looking in the direction indicated by the arrow; Fig. 5 is an enlarged partial sectional view substantially along the line 5—5 of Fig. 2, looking in the direction indicated by the arrow; Fig. 6 is an enlarged 45 partial sectional view substantially along the line 6—6 of Fig. 2, looking in the direction indicated by the arrow; Fig. 7 is a partial sectional view substantially along the line 7—7 of Fig. 2, looking in the direction indicated by the arrow; and Fig. 8 is a partial sectional view substantially along the line 8—8 of Fig. 2, looking in the direction indicated by the arrow.

Before describing in detail my improved

printing and addressing machine, this brief preliminary description may be given to facilitate the understanding of the construction and operation. The cards or blanks to be printed are placed in a suitable receptacle provided on the machine, and these cards are fed automatically and successively from the bottom of the pile forwardly to a platen which is arranged between a main printing device or reciprocating type carrying member which is designed to print the subject matter on the top face of each card, and a suitable plunger which is arranged below the platen and is adapted at each stroke to engage and raise an address plate 60 or slug so as to print the address on the lower side of the card, the two printing operations on opposite sides of the card taking place preferably simultaneously. The address plates or slugs are fed from a suitable 65 hopper, which may be filled from time to time, in substantially the same manner that the cards are fed forwardly to the platen. At each operation of the machine, the lowermost slug in the hopper is fed laterally and 70 when directly below the platen and above the slug moving plunger, it will be engaged by the latter and lifted upwardly so as to print the address carried thereby on the lower face of a card. After the printing 75 operation, this slug will be moved beyond the plunger and a new slug presented above the same, and at the same time the printed card is automatically moved from the platen, preferably into a suitable receptacle and a 80 new card is moved into position to be printed.

Referring now to the figures of the drawing, 10 represents a suitable base or bed plate which may be supported on a table or cabinet. Supported in suitable bearings 11 on the lower side of the bed plate is a shaft 12 which drives all the operating mechanism of the machine. This shaft which may be driven by a foot pedal, hand crank, or motor 95 is provided with a sprocket wheel 13 normally loose thereon, but which may be clutched to the shaft by a clutch member 14 adapted to be shifted by a yoke 15 and a forwardly projecting rod 16 having at its 100 end a hand wheel or grip 17. As shown in Fig. 2, this shaft 12 is located slightly to the rear of the center line of the bed plate. On the upper face of the bed plate are two parallel side plates 18 which 105

support a number of the operating parts and located between these side plates is a rectangularly shaped receptacle 19 adapted to receive the cards or blanks to be printed. 5 This receptacle will be of a height such that it will at one time accommodate a large number of blanks. In Fig. 5, a number of these blanks are shown at 20. The blanks are automatically fed forwardly from the bottom of the pile or from the lower part of the hopper onto a platen shown at 21, (to be referred to presently), by means of a pair of reciprocating fingers 22, which extend upwardly above the base substantially the 10 thickness of a blank, and are adapted to be shifted back and forth in two parallel slots 23 in the base, these slots extending transversely across the bottom of the receptacle and a suitable distance to the rear of the 15 latter, as shown in Fig. 2. These fingers 22 are carried by a reciprocating feeding plate 24 which engages the lower side of the base 10, and is guided and is held in position against the latter by means of a stationary 20 rod 25, (Figs. 2 and 3), along which the plate 24 slides, the plate having a suitable boss 26 provided with an opening through which the rod extends. The plate 24 is reciprocated by an arm 27 which is fixed to a 25 shaft 28 journaled in the upright side plates 18, this arm 27 being designed to swing back and forth through a suitable slot 29 in the base, and having a lower bifurcated end which engages a pin 30 carried by the plate 30 35. This shaft 28 has fixed thereto one or more cranks 31 each connected by an arm 32 which extends diagonally downwardly and forwardly through a slot 33 in the base and at its lower end is provided with a strap 34 which engages an eccentric 35 mounted on the shaft 12. The movement of this eccentric rocks the arm 32 in a manner such as to turn the shaft 28 and swing the arm 27 back and forth so as to reciprocate the feeding 40 45 plate 24.

As before stated, the cards are fed forwardly onto a platen 21. This platen which is arranged just in front of the card receptacle 19 and is preferably formed of rubber, 50 is provided with an elongated opening 35 through which the type of the addressing slugs are adapted to be projected, as will be explained presently, and the base plate has a suitable elongated opening 36 below the 55 opening 35 in the platen so as to permit the type on the address slugs to be raised into engagement with the lower faces of the blanks.

Arranged directly above the platen 21 is 60 a vertically reciprocating member 37 or main printing device which carries the type form for printing the subject matter on the top face of each blank. This member 37 is in the form of a yoke having upright arms 38 65 engaging vertical guide slots in arms 39

which project upwardly from the forward ends of the side plates 18, and this yoke is also provided with a lower central portion 40 having on its lower side, near opposite ends, dovetail or undercut projections 41 70 into which is adapted to be placed a type form 42, consisting of a plate having on its lower face the type for printing the subject matter. It is immaterial to the main features of the present invention whether the 75 type carried by the member 37 are inked by an inking pad or roll, or whether a ribbon is employed. In this case, the printing is accomplished by means of a ribbon 43 carried by rolls 44 supported by and movable with the 80 type carrier 37. This type carrying member 37 is adapted to be raised and lowered or reciprocated by a pair of levers 45 each of which is connected at its forward end to the member 37 by a pin or screw 46, and at its rear end engages a normally fixed rod 47 extending between the side plates 18. These levers 45 are reciprocated by vertically movable arms 48 85 pivotally connected at their upper ends to the levers 45 between the connections of the levers with the type carrying member 37 and the rod 47, and at their lower ends said arms are provided with cross heads 49 which are adapted to slide in guides 50 and which are provided with heart-shaped cam openings 51, the inner surface of each of which is engaged by a roller 52 carried by an arm 53 which is fixed to and rotates with the shaft 12. The action of the revolving rollers 52 on the cam surfaces 51 draws the arms 48 and levers 45 downward. The lever arms 45 are moved upward at the same rate of speed that they moved downward by coil springs 54 which surround the arms 48 and are located between the levers 45 and the base 10, these springs serving to maintain the roller and cam surface in engagement after the completion of the downward movement of the levers 45.

In order that the pressure of the type carried by the type carrying member 37 may be nicely adjusted, the rod 47 has an eccentric portion 47^a shown clearly in Fig. 2 and Fig. 3, and this eccentric portion engages within an elongated slot 45^a in the rear end of each of the levers 45. Fixed to one end of the rod 47, at the outer side of one of the side plates 18, is a disk or hand wheel 55 by which the rod 47 may be turned by hand. The rod 47 may be locked in any position by means of a lock nut 56 screwed onto the end of the rod 47.

The address slugs or plates shown at 57 and previously referred to are preferably separate and independent members each consisting of a metal plate 58 and addressing type 58^a. Each of the plates has along its side edges downwardly and inwardly bent portions forming feet 58^b adapted to slide along a guideway, to be referred to pres- 100

ently, and each may have an index tab 58^a, and may also have on its upper face suitable tabs 58^a adapted to hold a card 58^b on which may be printed or written the name and address to be printed by the type carried by the slug. These slugs are adapted to be supplied to and to be fed automatically from the hopper 59, which in Fig. 6 contains a number of slugs 57. When the machine is 5 in operation, the hopper 59 is in upright position, but in order that it may be tipped backward to facilitate the refilling of the hopper, the latter has near its lower end rearwardly extending arms 59^a which are 10 pivotally connected to upwardly projecting ears 60 on the base. To fill the hopper a suitable tray or drawer of slugs will be placed adjacent the upright hopper and then when the latter is tipped backwardly a suitable 15 distance, the slugs will be transferred from the tray or drawer into the hopper, and then the hopper may be again placed in an upright position so that the slugs may be fed therefrom one at a time from the bottom 20 of the pile. The lower end of the hopper when in upright position, extends into a depending recessed portion 61 in the front portion of the base, this recessed portion 61 having a slot extending toward the left, as 25 shown most clearly in Fig. 2, at right angles to the side plates 18. It may be here noted that this depressed or recessed portion 61 is in line with the platen and the slot therein forms a part of a guideway along which the 30 slugs are adapted to be moved,—the slugs when fed from the hopper being in a position such that the type 58^a carried thereby are directly in line and below the opening in the platen 21.

40 Before describing the mechanism for feeding the slugs from the hopper to the point where the printing is accomplished, it may be well to first describe the mechanism for raising the slugs one at a time, as they are 45 fed forward, so as to print the addresses.

Arranged directly below the platen 21 is a plunger 62 which raises the different address slugs upwardly one at a time, as the latter are fed onto the top of the same, so as to 50 project the type of the slugs through the opening in the platen and print the different addresses onto the lower faces of the blanks. This plunger 62 is guided for vertical movement toward and away from the platen by 55 a pair of L-shaped brackets 63 and 64 each having vertical legs provided on their adjacent or inner faces with grooves which are engaged by vertical ribs on opposite sides of the plunger, and these brackets are also provided 60 with horizontal legs which engage and are secured to the lower face of the bed plate 10 by screws 65. The horizontal portions of the brackets are in a line with each other and are provided with longitudinal recesses 65 which are in a line with the guide slot in

the recessed portion 61 of the base and form a continuation thereof, so that the slugs may slide from the bottom of the hopper through the groove or slot in the base, thence into the slot of the bracket 63, thence onto the 70 plunger, and after having been moved upward by the plunger and then lowered, into the horizontal slot of the bracket 64 from which the slugs may drop into a suitable receptacle. The plunger is given the necessary 75 reciprocating movement, which movement is not very great, by means of a lever 66 which is pivotally supported intermediate its ends on a rod or pin 67 supported in a pair of ears or lugs 68, (see Figs. 1, 2 and 5) extending downwardly from the base under the forward portion of the card receptacle 19. The reciprocating feeding plate 24 is notched, as shown by dotted lines in Fig. 2, so that the downwardly projecting lugs 68 80 will not interfere with the movement of the same. This lever 66 is bifurcated or forked at its forward end, and the ends of the bifurcated portion are connected to the slug moving plunger 62, by means of pins 69 85 which extend through elongated slots in the vertical portions of the brackets 63 and 64, as shown clearly in Fig. 3. The portion of the lever 66 at the rear of the supporting rod 67 extends downwardly and thence rearwardly below the operating shaft 12, and this rearwardly extending portion is adapted to be engaged by the nose or point of a cam 70 which is mounted on the shaft 12, as shown by dotted lines in Figs. 1, 2 and 3. 90 The engagement of the cam 70 with the rear end of the lever 66 depresses said rear end and causes the plunger to be moved upwardly so that the type carried by a slug is extended through the slot 36 in the base and 95 the slot 35 in the platen 21, causing said type to engage and print an address on the lower face of a card supported on the platen. The plunger 62 may be moved downwardly by gravity or by the action of a spring. 100

I have provided means for adjusting the pressure of slug or address type on the card, and this adjustment is similar to the adjustment for the pressure of the type carried by the type carrying member 37. The rod 105 67 which, as shown in Fig. 2, extends to the left of the ears 68, substantially to the left hand side of the bed plate, is provided between the ears 68 with an eccentric portion 72 shown most clearly in Fig. 3, which eccentric portion extends into an elongated slot 73 of the lever 66. In order to turn the rod 67 so as to adjust the pivotal center of the lever 66 I have provided at the left hand side of the base plate a vertical adjusting pin 74 which at its lower end is connected to a rearwardly extending finger 75 on the outer end of the rod 67. This pin 74 is threaded at its upper end and is engaged by an adjusting nut 76 arranged at 110

115

120

125

130

the top of the bed plate. By turning this nut 76, the pin 74 will be raised or lowered and the rod 67 supporting the lever 66 will be turned, turning the eccentric portion 72 in the slot or elongated opening of the lever.

The cams for operating the levers which actuate the type carrying members are so timed that the upper type carrying member 10 is lowered so as to print on the upper face of the card and the lower plunger is raised so as to print the address on the lower side of the card at the same time. Although the simultaneous printing is not absolutely necessary, it is preferable.

The slug feeding mechanism will now be explained.

When the slugs are placed in the hopper 59, and the latter is in upright position, the 20 lowermost slug rests on the bottom of the slot, or guideway in the portion 61 of the bed plate. These slugs are fed successively from the bottom of the pile and move laterally along the slot or guideway in the bed 25 plate and in the brackets 63 and 64 to and beyond the plunger 62 by means of a laterally moving spring finger 77, which is adapted to engage at substantially the middle of the upper end edge of the plate 58 of the slug. 30 This finger 77 is secured to the end of a member 78 which is adapted to be reciprocated in an elongated slot 79 in the bottom of the laterally extending slot in the portion 61 of the base, and this member 78 is reciprocated by a horizontally moving lever 35 80 which is connected to the member 78 near its forward end, is pivotally supported at its rear end on the lower side of the base by means of a pin 81, and is provided between its ends with a roller 82 which engages the face of a cam 83 supported on the shaft 12. When the cam 83 is rotated, it shifts the forward end of the lever 80 to the left, as viewed in Figs. 1 and 2, so as to feed 40 the slugs along the guideway, and although if desired, the cam 83 may be constructed so as to shift the lever in both directions, I have in this case provided a spring 84 which moves the forward end of the lever to its 45 right hand position.

I have provided for the cam 83 a driving connection between the latter and the shaft 12, of a nature such that this cam may be driven at two different speeds so that the 55 rate of feed of the address slugs can be varied. The cam 83 is fixed to the end of a boss of an internal gear member 85, which, together with the cam 83, are loose on the shaft 12. Within the gear member 85 60 is a gear 86, which is adapted to drive the gear 85 through a pair of idler gears 87 and 88 which are carried by a bracket 89 secured to the lower face of the base 10. A key 90, carried by a pin 91, extending loosely into the end of the shaft 12, is adapted to

slide through and project beyond a slot 92 in the shaft 12. Also the hub of the gear 86 is provided with a slot or notch 93 and the hub of the gear 85 is provided with a slot or notch 94, either of which notches is 70 adapted to receive the key 90. Between the two notches 93 and 94 is an intervening space 95, and when the pin 91 is so adjusted that the key 90 extends into this space 95, the cam 83 and consequently the 75 slug feeding mechanism are idle. When, however, the pin 91 is shifted inwardly so that the key 90 is in the notch 93 of the gear 86, then the gear 86 is driven directly by the shaft 12, and the gear 85 and the cam 80 83 are driven at a reduced speed by the gear 86 and the idler gearing 87 and 88. These gears are preferably so proportioned that when the key is in its outer position so as to cause the gear 85 to be driven directly 85 from the shaft 12, an address slug will be presented over the slug moving plunger 62 at each printing operation, and when the key is in its innermost position, the gear 85 and cam 83 are driven at one half the 90 speed above mentioned, so that a slug will be moved forwardly onto the slug moving plunger 62 at every other stroke of the type carrying member 37.

The purpose of this speed change in the slug feeding mechanism 95 is to permit the printing of an address twice on each card or other blank, either on the same or different sides. For example, when slugs are fed at the slow speed, one slug will be fed to a position above the plunger 100 and below the platen and will remain in that position during two strokes of the upper member 37. To print the different addresses twice on the different blanks, the machine may be used as an addressograph alone, in which case a dummy plate may be placed in the bottom of the member 37, and when a blank is placed manually on the platen at the first stroke of the members 37 and 62, an address will be printed on one 105 part of the blank, and then if the card is shifted or reversed side for side, the same address will at the next stroke of the members 37 and 62 be again printed on the card. If the key is left in the space between the notches 93 and 94, the addressing part of the machine will be idle, and the machine may then be used as an ordinary printing machine.

The speed changing pin 91 which carries 110 the key 90 may be adjusted axially of the shaft 12 by means of a pin 96 extending vertically through the bed plate and provided at its upper end with a button or knob 97 which may be turned by hand, and at its lower end with a crank pin 98 which engages in a groove 99 in the outer end of the pin 91.

In the use of the machine above described, a large number of cards will be placed in the card receptacle 19, and the hopper 59 will be 115 120 125 130

filled with address slugs, this latter being accomplished, as before stated, by placing a tray or drawer against the open face of the hopper, then tilting the hopper and tray 5 backwardly so that the slugs may slide from the tray or drawer into the hopper, and then again restoring the hopper to its upright position so that the lowermost address slug rests in the bottom of the slot of the bed 10 plate, in position to be engaged by the feeding finger. The machine may be then thrown into operation by the clutch 14 when the printing and addressing operations take place.

15 The cards are fed forwardly onto the platen in succession, the lowermost card of the pile being fed in each instance, and simultaneously with the forward movement of each card, an address slug is moved over 20 the plunger, after which the card supported on the platen has the subject matter printed on its upper face by the downward movement of the type carrying member 37, and the particular address slug directly over the 25 plunger will be raised, and the type will be projected through the openings 35 and 36 in the platen and bed plate respectively, so that the address will be printed on the lower face of the card,—the two printing operations 30 taking place preferably simultaneously. After the card is printed and the two type carrying members move upwardly and downwardly respectively away from the printed card, a new card is fed onto the platen, moving the printed card forwardly so 35 that it may drop into a suitable receptacle and another address slug is moved by the feeding mechanism over the plunger 62, causing the address slug which had been 40 previously used to be moved to the left of the plunger to a position such that it may drop into a suitable receptacle. It will be noted that the upper face of the plunger 62 is of a size such that in rising, it will pass 45 between the inwardly bent portions at the bottom of the slug and engage the inner face of the type carrying plate.

As the cards in the receptacle 19 are exhausted, this receptacle may be filled from 50 time to time, and when the hopper is emptied, or substantially emptied, it may be refilled by transferring the slugs from a suitable drawer or tray into the hopper in a manner before stated.

55 In case there is any variation in the thickness of the cards or of the address slugs, or if for any other reason it is desired to adjust the pressure of the type on the faces of the cards, this can be easily accomplished by 60 turning slightly either the rod 47 which pivotally supports the levers 45, or the rod 67 which pivotally supports the lever 66, or both these levers may be adjusted in this manner.

65 The printing and addressing machine

above described is very strong and durable. None of the parts are especially complicated or are liable to get out of order. This machine is very efficient, inasmuch as cards or blanks can be printed very effectively and 70 with great rapidity,—the machine requiring practically no attention of the operator, except in refilling the card receptacle 19 and the hopper 59.

I do not desire to be confined to the exact 75 details shown, but aim in my claims to cover all modifications which do not involve a departure from the spirit and scope of my invention.

Having thus described my invention, what 80 I claim is:

1. In a printing machine, a blank holder adapted to support blanks when in printing position, a main printing device adapted to print the same subject matter on one side of 85 each of a number of blanks placed successively on the blank holder, and a member movable toward and away from the blank holder and adapted to receive one at a time and to move toward the blank holder separate and unconnected printing slugs fed into the path of movement of said member so as to cause said slugs to print on the opposite sides of the blanks, and means for feeding the slugs from a source of supply into the 95 path of movement of said member.

2. In a printing and addressing machine, a platen having an opening therein, a movable member on one side of the platen and carrying a type form for printing matter on 100 one side of each of a number of blanks placed successively on the platen, a movable member on the opposite side of the platen and adapted to move address slugs toward the platen and project type carried thereby 105 through the opening of the platen so as to print addresses on the opposite sides of the blanks, and means for feeding the slugs one at a time in the path of said slug moving member.

3. In a printing machine, a blank holder having an opening therein, a movable member arranged above the blank holding member and having a type form adapted to print on the upper face of each of a number of 115 blanks, a device arranged below the blank holder and movable toward and away from the same, and means for feeding printing slugs successively onto said device so as to cause the latter to raise the slugs successively 120 and project type carried thereby through the opening in the blank holder so as to print on the lower face of each of the blanks.

4. In a printing and addressing machine, a blank holder having an opening therein, 125 a main printing device adapted to print on the upper face of each of a number of blanks, a plunger arranged below the blank holder, means for feeding separate address slugs in the path of said plunger, and operating 130

mechanism for causing said plunger to be raised and lift an address slug so as to print on the bottom face of a blank simultaneously with the printing on the upper face 5 of the blank.

5. In a printing and addressing machine, a platen having an opening therein, a main printing member adapted to print on one side of each of a number of blanks, a hopper 10 adapted to be provided with a number of address slugs, means for feeding the slugs from the hopper along beneath the platen, and a reciprocating member adapted to raise the slugs successively so as to print on the 15 opposite faces of the blanks as said slugs are moved to a position between the platen and the plunger.

6. In a printing and addressing machine, a platen having an opening therein, a main 20 printing member adapted to print on one side of each of a number of blanks, a hopper adapted to be provided with a number of address slugs, means for feeding the slugs from the hopper along beneath the platen, a reciprocating member adapted to raise the 25 slugs successively so as to print on the opposite faces of the blanks as said slugs are moved one at a time to a position between the platen and the plunger, and means, for simultaneously actuating said main printing 30 device and said plunger.

7. In a printing and addressing machine, a platen having an opening therein, a receptacle for blanks, means for automatically 35 feeding the blanks successively from the receptacle to the platen, a main printing device adapted to print matter on one side of each of the blanks when placed on the platen, means for feeding address slugs along the 40 lower side of the platen, and a device for raising each address slug so as to project the type carried thereby through the opening of the platen and print on the opposite face of a card.

45 8. In a printing and addressing machine, a platen having an opening therein, a receptacle for blanks, means for automatically feeding the blanks successively from the receptacle to the platen, a main printing device adapted to print matter on one side of each of the blanks when placed on the platen, means for feeding address slugs along the lower side of the platen, and a device for raising each address slug so as to 50 project the type carried thereby through the opening of the platen and print on the opposite face of a blank, and mechanism for actuating the main printing device and said slug lifting device so that the printing operations will take place on both sides of the blank substantially simultaneously.

60 9. In a printing and addressing machine, a platen or blank holder having an opening 65 therein at printing position, a receptacle for blanks, a receptacle adapted to receive ad-

dress slugs, a main printing device on one side of the platen, and a slug raising device on the opposite side of the platen, mechanism for feeding the blanks one at a time from the blank receptacle onto the platen, 70 and mechanism for feeding the slugs from the slug receptacle and for causing them to be brought one at a time into the path of the slug raising device so that on the actuation of the latter the slugs print on the 75 lower sides of the blanks.

10. In a printing and addressing machine, a platen adapted to support a card while being printed and provided with an opening therein, a receptacle for blanks, a receptacle for address slugs, a main printing device arranged above the platen adapted to print on the upper faces of the blanks, a slug lifting device arranged below the platen, means for feeding the cards one at a time 80 from the receptacle onto the platen, means for feeding the slugs from the hopper along the lower side of the platen above said slug lifting device, and mechanism for operating said main printing device and slug raising 85 device so that addresses will be printed on the lower sides of the blanks simultaneously with the printing on the upper sides of the blanks.

11. In a printing and addressing machine, a base plate, a receptacle for blanks, a platen or blank supporting member arranged in front of the receptacle and having an opening therein, a main printing device arranged over the platen and adapted to be moved toward and away from the same, a hopper adapted to be supplied with slugs arranged at the side of the platen, a guideway in the bed plate extending laterally from the hopper toward and in line with the platen, a slug lifting device arranged below the platen adapted to be moved toward and away from the same, a reciprocating feeding device for feeding the blanks one at a time from the lower part of the blank receptacle onto the platen, a reciprocating feeding device adapted to feed the slugs one at a time from said hopper through the guideway, and mechanism for actuating the main printing device so as to print the same subject matter 95 on the upper face of each of the cards, and for actuating the slug lifting device so as to raise the slugs successively to the blanks as the slugs are fed one at a time over said slug lifting device, and print on the lower faces 100 of the cards.

12. In a printing and addressing machine, a platen having an opening therein and adapted to support a blank during the printing operation, a main printing device adapted to print on one side of each of the blanks, a reciprocating device arranged below the platen and adapted to be moved toward and away from the same, means for feeding address slugs between the platen and said re- 125

ciprocating device so that the latter may raise the same one at a time and print on the lower face of each of the cards, and means for varying the rate of feed of the slugs.

- 5 13. In a printing and addressing machine, a base plate, a blank holder having an opening therein, a main printing device arranged above the blank holder, an address slug lifting device arranged below the blank holder, 10 a hopper for address slugs arranged at one side of the blank holder, said hopper being pivotally supported from the bed plate so that it may be tilted backward or raised to a substantially upright position, a guideway 15 between the hopper and the blank holder, and mechanism for feeding the slugs from the lower part of the hopper along said guideway, so that said slugs are presented one at a time above the slug lifting device. 20 14. In a printing and addressing machine, a platen having an opening therein, a main printing device, and an address slug lifting device arranged on opposite sides of the platen and adapted to be moved toward and 25 away from the same, means for feeding address slugs one at a time between the platen and the slug lifting device, means for operating the main printing device and slug lifting device comprising pivoted levers, and 30 eccentric members supporting said levers, and means for adjusting said eccentric members so as to vary the pressure of the type upon a blank.

35 15. In combination, an upper vertically reciprocable plunger and upper type holder, a platen thereunder spaced therefrom and having an opening for printing, a support for a lower type holder underneath said platen and opening, a separate receptacle 40 for lower type holders from which they fall by gravity, and an automatically acting device adapted to feed said lower type holders from said receptacle to said support.

45 16. In combination, in a machine for printing on opposite sides of stock to be printed, a main printing member for printing the same data repeatedly on the stock, a magazine for containing a plurality of 50 separate printing devices for printing different data on the stock, said main printing member being on one side of the stock and the printing devices being on the opposite side of the stock when the printing impressions are made, feeding means for feeding said printing devices from the magazine to printing position, and mechanism for causing the type of both the main printing member and separate printing devices to be 55 impressed against the stock.

60 17. In combination, a main printing member for printing on the upper sides of blanks, a platen beneath said printing member and having an opening through which type may be projected, a magazine for con-

taining a plurality of separate printing devices for printing on the lower sides of the blanks, means for feeding the separate printing devices, and means for causing the type of said separate printing devices to be 70 projected through the opening of said platen.

75 18. In combination, a main printing member for printing on the upper sides of blanks, a magazine for containing a plurality of printing devices for printing on the lower sides of the blanks, a magazine for containing blanks to be printed, the main printing member being above and the printing devices being below the blanks 80 when the printing impressions are made, and mechanism for feeding said printing devices from the magazine containing them to printing position beneath the blanks, for feeding the blanks from the magazine, and 85 for causing printing impressions to be made from said main printing member and from said printing devices.

90 19. In combination, a main printing member for printing on the upper sides of blanks, a platen having an opening beneath said printing member, a magazine for containing a plurality of printing devices for printing on the lower sides of the blanks, a magazine for containing a plurality of 95 blanks, and mechanism for feeding the blanks on to the platen, for feeding the printing devices from the first named magazine to printing position beneath said platen, for causing the type of the upper 100 printing member to be pressed against the upper sides of the blanks and for causing the type of said printing devices to be pressed against the lower sides of the blanks.

105 20. In combination in a printing and addressing machine, a platen having an opening therein, a main printing member for printing on the upper sides of blanks, a magazine for containing a plurality of printing devices for printing names and 110 addresses on the lower sides of the blanks, a magazine for containing a plurality of blanks, and mechanism for feeding blanks on to the platen, for feeding the printing devices from the first named magazine to 115 printing position beneath the platen and for causing the type of the main printing member and of said printing devices to be projected against the upper and lower sides of the blanks.

120 21. In combination in a printing machine, a main printing member for printing data on one side of stock to be printed, a magazine for containing a plurality of auxiliary printing devices for printing on the opposite side 125 of the stock, a source of supply of stock on which printing is to be done, and mechanism for feeding the stock, for feeding said printing devices from the magazine containing them to printing position, and for causing

the type of said main printing member and of said printing devices to be impressed against the upper and lower sides of the stock.

- 5 22. In combination, an upper main printing member for printing the same data on the upper sides of blanks, a magazine for containing a plurality of printing devices for printing names and addresses on the 10 lower sides of the blanks, a guideway for said printing devices extending from said magazine, a magazine for containing a plurality of blanks on which the printing is to be done, and mechanism for feeding the printing 15 devices for feeding the blanks across the guide-way and for causing the type of the main printing member and of said printing devices to be impressed against the upper and lower sides of the blanks respectively.
- 20 23. In combination, a main printing member for printing the same data on one side of a plurality of blanks, a magazine for containing a plurality of separate printing devices for printing different data on the opposite side of the blanks, means for feeding said printing devices along a given path, a magazine for blanks, means for feeding the blanks past the main printing member and past said printing devices, said main printing 25 member being on one side of the blanks and the printing devices being on the opposite side of the blanks when printed, and mechanism including operating parts acting 30 in timed relationship for operating the 35 feeder for the printing devices, the feeder for the blanks and for causing the type of the main printing member and of the printing devices to be impressed against opposite sides of the blanks.
- 40 24. In combination, a main printing member for printing the same data on one side of a number of blanks, a magazine for containing a plurality of separate printing devices for printing different data on the opposite 45 side of the blanks, means for feeding said printing devices along a given path, a magazine for containing blanks to be printed, means for feeding the blanks along a path at right angles to the path of movement of the 50 printing devices, and a pressure device for causing printing impressions to be made on the blanks successively from the different printing devices, said main printing member and printing devices being on opposite sides 55 of the blanks when printing.

25. In combination, a main printing member for printing the same data on the upper sides of the blanks to be printed, a magazine for containing a plurality of printing devices for printing on the lower sides

of the blanks, means for feeding said printing devices along a given path, a magazine for containing a plurality of blanks to be printed, means for feeding the blanks so that they will pass above the separate printing devices and beneath said main printing member, a pressure device for causing printing impressions to be made on the lower side of the blanks successively from the different printing devices, and means for operating the main printing member, the feeding means for the separate printing devices, the feeding means for the blanks and said pressure device.

26. In a printing machine, a main printing member for printing the same data on the upper side of stock to be printed, a magazine for containing a plurality of separate printing devices for printing on the lower side of the stock, means for feeding the printing devices from the magazine along a given path, a source of supply of stock adapted to be fed over the path of movement of the separate printing devices and beneath said main printing member, a pressure device for causing a printing impression to be made on the stock from each of said separate printing devices when the latter reaches a given position in its path of movement, and coöperating means for actuating said main printing member, the feeding means for the separate printing devices and said pressure device, so that stock is printed on opposite sides.

27. In combination in a printing machine, an upper printing member for printing the same data on the upper sides of blanks, a magazine for containing a plurality of separate printing devices for printing different data on the lower sides of the blanks, means for feeding said separate printing devices along a given path, a magazine for containing said blanks, means for feeding said blanks across and above the path of movement of said separate printing devices, a reciprocating pressure device for causing a printing impression to be made on the lower side of a blank from each printing device when it reaches a given position in its path of movement, and means for operating said main printing member, the feeding means for the separate printing devices, the feeding means for the blanks and said pressure device in predetermined timed relationship.

In testimony whereof, I hereunto affix my signature in the presence of two witnesses.

RICHARD G. THOMAS.
